RADIATOR

Allen P. Livar, Montclair, N. J., assignor, by direct and mesne assignments, of one-half to Richmond Radiator Company, New York, N. Y., a corporation of Delaware and one-half to Sears, Roebuck and Co., Chicago, Ill., a corporation of New York

Continuation of application Serial No. 655,235, February 4, 1933. This application October 14, 1935, Serial No. 44,837

13 Claims. (Cl. 257—151)

The invention pertains to radiators of the type used in space heating, and one object thereof is to provide a radiator which, while composed of separate cast sections, presents the appearance of a closed cabinet except for the provision in the upper part of its front wall of an ornamental grille, and which provides, moreover, for a substantially unrestricted flow through the radiator of a large volume of air which is effectually heated in its passage and then discharged forwardly through the grille in the form of a multiplicity of superimposed air streams, whereby to produce a rapid and effectual mixing of the air with the room air.

Another object is to provide a radiator of the character indicated which, because of its high efficiency as a heat exchanger, may be made substantially smaller than prior radiators of like capacity so that it requires a smaller amount of space and is capable of being supplied at a lower cost.

The objects of the invention thus generally stated, together with other and ancillary advantages, are attained by the construction and arrangement shown by way of illustration in the accompanying drawing and hereinafter described as the preferred embodiment of the invention. In the drawing:

Figure 1 is a perspective view of a radiator constructed in accordance with my invention.

Fig. 2 is a perspective view of one of the sections composing the radiator.

Fig. 3 is a horizontal plan section taken approximately in the plane of line 3—3 of Fig. 1.

Fig. 4 is an inner side elevational view of one of the end sections of the radiator.

The improved radiator is composed of a plurality of separately cast vertically elongated sections secured together side by side to form a generally rectangular cabinet-like structure. Preferably the individual sections are, in so far as possible, made uniform in character for the sake of economy in manufacture, and as shown they comprise two opposite end sections 10 and 10' and a plurality of intermediate sections 11, the latter being identical, and the former of the same construction except for the reversal required because of their use at opposite ends of the structure. Each of the sections is in the form of a hollow body and when the sections are assembled they provide a plurality of vertically elongated heating chambers 12 of substantial depth in a front to rear direction and spaced apart laterally so as to form intervening air spaces of corresponding depth for the passage

through the radiator of the air to be heated. When the radiator is to be positioned upon the floor of a room, the end sections are extended somewhat below the intermediate sections and, if desired, shaped to provide suitable supporting legs as shown in Fig. 1.

Referring now to Fig. 3, the heating chambers 12 are formed by thin side walls 13 spaced a short distance apart laterally, and outer edge walls 14. In order to present the appearance of a substantially closed cabinet, laterally extending flanges 15 are cast integral with the edge walls 14, which flanges engage one another in abutting relation. Said flanges therefore serve to define the outer edge walls of the aforesaid intervening air spaces.

It will, of course, be understood that the heating chambers 12 are interconnected for the circulation of a heating medium such as steam or hot water. The construction employed for this purpose, being well understood in the art, need not be described in detail. As shown, upper and lower bosses 16 and 16' (Fig. 2) are provided for the reception of the conventional connecting nipples; and inlet and outlet openings 17 are provided in the inner and outer side walls of the end sections in the depending portions thereof as shown in Fig. 1. In securing the sections of the radiator together, the usual tie rods 18 may conveniently be threaded through the openings formed by the bosses 16 and 16'.

An important feature of my invention resides in providing for a substantially uniform distribution over the heated surfaces of the radiator of a large volume of air passing through the radiator; for a rapid and effectual transmission of heat to the air in its passage; and for a control of the air in its discharge from the radiator in order to effect a proper mixture thereof with the air in the lower portion of the room. For this purpose the heating chambers have cast integral with their side walls a multiplicity of thin heat-conducting fins coacting with said side walls to provide in each of the air spaces a multiplicity of air passages 20 communicating at their lower ends with air inlet openings 21 and extending upwardly one behind the other in parallel relation and thence horizontally forward in superimposed relation, terminating in vertically elongated upper discharge openings 22 in the upper part of the front wall of the radiator. To form the inlet openings 21 and the discharge openings 22, the flanges 15 are appropriately interrupted at the bottom and upper front sides of the radiator, each of the openings being of a

vertical length approximately corresponding to the front to rear depth of the radiator.

While the construction and arrangement employed to provide the passages 20 for each of said air spaces may vary, in the preferred embodiment the aforesaid fins are in the form of a plurality of continuous solid ribs 23 of uniform width and corresponding to the width of the edge flanges 15. Like said flanges the ribs 23 are cast integrally with the thin side walls 13 of the heating chambers, with the ribs and flanges on adjacent sections terminating in abutting engagement in a transverse plane midway between the heating chambers 12 or centrally of the air passages 20. Also, it will be observed that, after extending upwardly a substantial distance from the lower to the upper portion of the radiator, the ribs 23 curve gently forward in such upper portion of the radiator so as to terminate in vertically spaced relation lengthwise of the corresponding discharge opening 22. Thus the front flanges 15 and ribs 23 coact with the side walls of the heating chambers to form a multiplicity of laterally closed flues whereby the moving body of air passing upwardly through the radiator is divided in a front to rear direction and then horizontally so as to effect a substantially uniform distribution of the air in its passage through the radiator. At the same time, the flanges 15 and ribs 23 constitute thin heat-radiating fins for the effectual transmission of heat to the air. Any retardation in the flow of the air in its passage occurs in the upper curved portions of the passages, which is the hottest part of the radiator.

As will be observed from Fig. 3 of the drawing, the lateral spacing between the heating chambers 12 is substantially greater than the thickness of said chambers, being in the present instance on the order of twice as great as the intermediate sections of the radiator. Also the width of the passages is correspondingly greater than the depth thereof as determined by the spacing of the ribs 23 relative to each other and to the edge flanges 15. Such proportioning of the parts has the effect of exposing the air passing through the radiator to heated surfaces having a large combined area and intimately related to the heating chambers for the effectual transmission of heat from the heating medium circulating through such chambers. Moreover, the vertical spacing of the ribs 23 at the point of discharge of the air through the openings 22 being relatively small, a positive directional control is imparted to the air as it discharges forwardly from the radiator, thereby insuring the travel of the air forwardly from the radiator for a substantial distance and the effectual mixing thereof with the air in the lower portion of the room.

By making the edge flanges 15 and the ribs 23 of uniform depth, their edges may be conveniently machined as by disk grinding to a smooth flat surface so that when the sections of the radiator are secured tightly together in assembled relation, the joints between the sections may be rendered substantially invisible particularly when the outer surface of the radiator is painted or enameled. Preferably, the passages 20 are of uniform cross sectional area and form throughout their lengths, so as to facilitate cleaning thereof.

In order to lend rigidity to the construction, especially in view of the fact that the side walls of the heating chambers are made very thin, a

suitable number of stays 24 (Fig. 3) may be provided between the walls of such chambers.

It has been found that radiators constructed in the manner set forth are highly efficient from the standpoint of heat exchanging capacity, with the result that the amount of metal required in constructing the radiator is substantially smaller than in the case of ordinary or conventional cast metal radiators. Moreover, the amount of space consumed thereby is substantially reduced. Apparently, the high degree of efficiency obtained is due to the large volume of air circulated through the radiator in intimate contact with the walls of the flues or passages 20 which serve to distribute the air substantially uniformly in its passage through the radiator. The vertically elongated portions of the passages operate with a chimney effect, thereby inducing the flow of a large volume of air which is discharged forcibly through the front discharge openings 22. Accordingly, the radiator operates largely upon the principle of convection.

A further and important advantage flowing from the construction employed is that the radiator provides a much more attractive appearance than prior cast metal radiators and avoids the necessity of separate sheet metal covers where an ornamental appearance is desired. And from this standpoint of appearance, it will be observed that the air discharge openings with the ends of the ribs 23 terminating therein, may be so coordinated with the forward edge walls of the heating chambers as to provide a grille work of very pleasing appearance. Thus, with the arrangement of parts shown in Fig. 1, where in the ends of the ribs 23 terminate substantially flush with the front edge walls of the heating chambers, the effect of a cross bar grille is obtained.

For the sake of uniformity of appearance, the end sections 10 and 10' are preferably constructed so that the heating chambers provided thereby are made of substantially greater thickness than the intermediate chambers.

This application is a continuation of my co-pending application Serial No. 655,235, filed February 4, 1933.

I claim as my invention:

1. A heat exchanger comprising a plurality of cast sections each having a relatively narrow and elongated chamber for heated fluid, said sections connected together for circulation of fluid through the sections in succession, and edge and internal fins projecting from each section toward an adjacent section and together forming walls of vertically extending laterally closed elongated open-ended flues of substantial length, said internal fins having portions curved to cause said air to be discharged forwardly in a horizontal direction, and said edge fins forming outer surfaces for the exchanger simulating a cabinet which surfaces are uninterrupted except for a grille formed by the open ends of the curved portions of said flues in the front of the simulated cabinet.

2. A heat exchanger consisting of a plurality of elongated cast sections, each section being formed to provide a chamber for heated fluid, means connecting said sections together so that said fluid may circulate through said sections in succession, and fins projecting from the sides of certain of said sections and contacting with matching fins on said adjacent sections, said fins being formed so as to provide an uninterrupted outer closed wall throughout the lower portion of said exchanger, and to provide a multiplicity of

smooth walled flues opening outwardly through said exchanger above said uninterrupted surface and continuing downwardly to points adjacent the bottom of the exchanger, said flues being open 5 adjacent said bottom.

3. A heat exchanger consisting of a multiplicity of cast sections each including a chamber for heated fluid and continuous fins projecting laterally therefrom into contact with matching fins of 10 an adjacent section to form flues, said sections being formed externally so as to present the appearance of a cabinet all of the walls of which are imperforate except the upper part of the front wall which simulates a grille, said grille being 15 formed by the open ends of flues formed by the fins on the sections, and said fins terminating adjacent the lower part of the exchanger, said flues having smooth walls and being of substantially the same cross sectional area from end to 20 end whereby they may be readily cleaned.

4. An end section for a heat exchanger made up of a multiplicity of cast sections comprising a hollow body formed to provide a chamber for heating fluid, the top, sides and edges of said 25 body being relatively flat surfaces, fins projecting from one side only of said body and forming flues extending lengthwise of said body and then toward one edge thereof, and a connection for a conduit communicating with said chamber at the 30 side of said body from which said fins project.

5. The end section defined in claim 4 including a fin that forms a smooth continuation of the top and edge walls of said chamber at the side at which said fins are formed, said fins being 35 interrupted only for the openings of said flues.

6. A heat exchanger comprising a plurality of cast sections each having a relatively narrow and elongated chamber for heated fluid, said sections being connected together for circulation of fluid 40 through the sections in succession, and edge fins projecting from each section toward and contacting with a matching fin on an adjacent section so as to form a relatively smooth wall at the front and top of said exchanger interrupted 45 adjacent the top of said exchanger, and a multiplicity of internal fins projecting from each section toward and contacting with a matching fin on an adjacent section, said last named fins terminating substantially in the plane of said 50 wall at the interrupted part thereof and forming a multiplicity of open flues presenting the appearance of a grille at the front of said exchanger.

7. A cast metal radiator comprising a plurality of vertically elongated sections secured together 55 side by side and forming a cabinet having a closed top wall and a closed front wall with laterally spaced vertically elongated air discharge openings in the upper part of its front wall and laterally spaced horizontally elongated openings 60 in its bottom side, said sections providing between said openings a plurality of narrow vertically elongated heating chambers of substantial depth with intervening air spaces terminating in said openings, and a plurality of heat-conducting fins cast integral with the side walls of the heating chambers and serving to divide each of said intervening air spaces into a multiplicity of air passages extending upwardly from near the lower portion of the 65 radiator and forwardly near the upper portion thereof toward said discharge openings, the fins defining the upwardly and forwardly extending portions of said passages being in the form of continuous parallel ribs disposed one above the other and terminating adjacent said discharge 70 openings whereby to direct the air forwardly beyond the radiator into superimposed streams.

8. A cast metal radiator comprising a plurality of vertically elongated sections secured together side by side and forming a cabinet having a closed top wall and a closed front wall with laterally spaced vertically elongated air discharge openings in the upper part of its front wall and laterally spaced horizontally elongated openings in its bottom side, said sections providing between said 10 openings a plurality of narrow vertically elongated heating chambers of substantial depth with intervening air spaces terminating in said openings, and a plurality of heat-conducting fins cast integral with the side walls of the heating chambers and serving to divide each of said intervening air spaces into a multiplicity of air passages extending upwardly from near the lower portion of the radiator and forwardly near the upper portion thereof toward said discharge openings, the forward ends of said fins coating with the forward edges of the heating chambers 15 between the air discharge openings to form an ornamental grille.

9. A cast metal radiator comprising a plurality of vertically elongated sections secured together side by side and forming a cabinet having laterally spaced vertically elongated air discharge openings in the upper part of its front wall and laterally spaced horizontally elongated openings in its bottom side, said sections providing between said 20 openings a plurality of vertically elongated heating chambers of substantial depth with intervening air spaces terminating in said openings, and a plurality of heat-conducting fins cast integral with the side walls of the heating chambers and serving to divide each of said intervening air spaces into a multiplicity of air passages extending upwardly from near the lower portion of the radiator and forwardly near the upper portion thereof toward said discharge openings, the fins defining the upper forward portions of said 25 passages being in the form of continuous vertically spaced ribs with rear end portions curving gently 30 downward.

10. A cast metal radiator comprising a plurality of vertically elongated sections secured together side by side and forming a substantially rectangular cabinet having laterally spaced vertically elongated air discharge openings in the upper part of its front wall and laterally spaced horizontally elongated openings in its bottom side, said sections providing between said 35 openings a plurality of vertically elongated heating chambers of substantial depth with intervening air spaces terminating in said openings, and a plurality of heat conducting fins cast integral with the side walls of the heating chambers and serving to divide each of said intervening air spaces into a multiplicity of air passages extending upwardly from near the lower portion of the radiator and forwardly near the upper portion 40 thereof toward said discharge openings, the fins defining the upwardly and forwardly extending portions of said passages being in the form of continuous parallel ribs disposed one above the other and terminating adjacent said discharge 45 openings whereby to direct the air forwardly beyond the radiator into superimposed streams.

11. A cast metal radiator comprising a plurality of vertically elongated sections secured together side by side and forming a substantially rectangular cabinet having laterally spaced vertically elongated air discharge openings in the upper part of its front wall and laterally spaced horizontally elongated openings in its bottom side, said sections providing between said 50 openings a plurality of narrow vertically elongated heating chambers of substantial depth with intervening air spaces terminating in said openings, and a plurality of heat-conducting fins cast integral with the side walls of the heating chambers and serving to divide each of said intervening air spaces into a multiplicity of air passages extending upwardly from near the lower portion of the radiator and forwardly near the upper portion 55 thereof toward said discharge openings, the fins defining the upwardly and forwardly extending portions of said passages being in the form of continuous parallel ribs disposed one above the other and terminating adjacent said discharge 60 openings whereby to direct the air forwardly beyond the radiator into superimposed streams.

75

ings a plurality of narrow vertically elongated heating chambers of substantial depth with relatively wide intervening air spaces terminating in said openings, and a plurality of heat conducting fins cast integral with the side walls of the heating chambers and serving to divide each of said intervening air spaces into a multiplicity of air passages extending upwardly from near the lower portion of the radiator and forwardly near the upper portion thereof toward said discharge openings, said passages being of a lateral width approximately twice the width of said heating chambers.

12. A cast metal radiator comprising a plurality of vertically elongated sections secured together side by side and forming a substantially rectangular cabinet having laterally spaced vertically elongated air discharge openings in the upper part of its front wall and laterally spaced horizontally elongated openings in its bottom side, said sections providing between said openings a plurality of narrow vertically elongated heating chambers of substantial depth with relatively wide intervening air spaces terminating in said openings, and a plurality of heat conducting fins cast integral with the side walls of the heating chambers and serving to divide each of said intervening air spaces into a multiplicity of air passages extending upwardly from near the lower portion of the radiator and forwardly near the upper portion thereof toward said discharge openings, said passages being of a depth in a front to rear direction substantially less than the lateral width thereof.

13. A cast metal radiator comprising a plurality of vertically elongated sections secured together side by side to form a cabinet-like structure and having a plurality of narrow vertically disposed heating chambers of substantial depth in a front to rear direction and a plurality of relatively wide intervening air spaces of a depth substantially corresponding to the heating chambers, said heating chambers having thin flat side walls and outer edge walls with laterally projecting edge flanges defining edge walls for said air spaces and coacting with the edge walls of the heating chambers to form substantially smooth outer surfaces for the front and top walls of the radiator, said edge flanges being interrupted at the bottom of the radiator to form laterally spaced air inlet openings communicating with the respective air spaces and being interrupted at the upper front side of the radiator to form laterally spaced air discharge openings for the respective air spaces of a vertical height approximately corresponding to the front to rear depth of the air chambers, each of said heating chambers having cast integral with the side walls thereof a multiplicity of thin solid heat conducting fins coacting to form a multiplicity of air passages extending upwardly in parallel relation from the lower portion of the radiator and forwardly near the upper portion thereof so as to direct the air forwardly through said discharge opening in a plurality of superimposed streams. 25
